UNITED STATES PATENT OFFICE.

PAUL EDWARD HITZIGRATH, OF ROCKVILLE CENTER, NEW YORK.

PACKAGE.

1,352,962.

Specification of Letters Patent. Patented Sept. 14, 1920.

Application filed April 2, 1920. Serial No. 370,722.

To all whom it may concern:

Be it known that I, PAUL E. HITZIGRATH, a citizen of the United States, and a resident of Rockville Center, in the county of 5 Nassau and State of New York, have invented a new and Improved Package, of which the following is a full, clear, and exact description.

This invention relates to improvements 10 in packages, and more particularly to an envelop designed as a container for hair nets, an object of the invention being to provide an improved construction of envelop which, when folded, will smoothly 15 support the hair net and prevent contact of sections of the hair net with each other so as to overcome any tendency to tangle the net.

A further object is to provide an envelop 20 of the character stated which can be manufactured and sold at a reasonably low price, and which will operate as a convenient container to inclose the net or which may be conveniently opened to display the net.

25 A further object is to provide an envelop that will act as a sanitary form of container for the net. In showing the net to the consumer it will not be necessary for the salesperson to remove the net from the container 30 or touch it with the hands as half of the net can be displayed at a time by unfolding either the left or right side half section flap or wing.

The envelop also lends itself readily for 35 imprinting or lithographing upon either side when open flap.

With these and other objects in view the invention consists in certain novel features of construction, and combinations and arrangements of parts, as will be more fully 40 hereinafter described and pointed out in the claim.

In the accompanying drawings—

Figure 1 is a plan view showing the envelop in open position to display the net.

Fig. 2 is a perspective view showing the parts partially folded.

Fig. 3 is an exaggerated view in section through the envelop and the net showing 50 the parts in folded and closed position.

Fig. 4 is a view in transverse section on the line 4—4 of Fig. 3.

55 My improved package comprises an envelop composed of a single sheet or blank 1 having integral tabs or folds 2 at its side edges with a fold line 3 between the

main portion of the blank and the tabs or folds 2. A fold line 4 extends centrally through the folds 2 and through the main portion 1 of the blank and also through a 60 covering sheet 5 which is of substantially the same width as the main portion of the blank 1 but is slightly shorter and is adapted to be positioned on top of the hair net 6.

An integral covering tab or flap 7 is made 65 integral with the upper edge of the blank 1 and is provided with a tongue 8 adapted to be positioned through a slit 9 in the blank when the envelop is folded. The inner face of this tab 7 is also provided with adhesive 70 as indicated at 10, so that the envelop can be sealed if desired.

The hair net 6 is of general circular form and is of such diameter or length that while the intermediate portion of the net rests 75 upon the main portion of the blank 1, the end portions of the net extend over onto the tabs or folds 2. When the sheet 5 is positioned over the net and the tabs 2 folded down upon the sheet 5, the ends of the net 80 6 are disposed between the sheet 5 and the tabs or folds 2. While in this position, the envelop is folded upon the line 4 and the covering tab or flap 7 is either secured by its adhesive or its tongue 8 is positioned 85 through the slit 9, as clearly shown in Fig. 3.

It will thus be noted that the hair net will be maintained in smooth condition without any parts of the net touching each 90 other, and when the envelop is opened and spread out, the net can be displayed without any danger of tangling the net.

Furthermore, this manipulation of opening and closing the envelop can be performed without the hands coming into contact with the net, hence, the device is extremely sanitary. When the envelop is folded and closed, it is a secure container 95 for the net.

100 Various slight changes might be made in the general form and arrangement of parts described without departing from the invention, and hence I do not limit myself to the precise details set forth, but consider myself at liberty to make such changes and alterations as fairly fall within the spirit and scope of the appended claim.

I claim:

110 As a new article of manufacture, a package comprising a blank having a pair of parallel fold lines spaced from the edges

thereof and having a central longitudinal fold line at right angles to the first mentioned fold lines, a hair net located on the central portion of the blank with its ends 5 extending over said parallel fold lines, a covering sheet on the net between said parallel fold lines, the ends of the net and the ends of the blank outside of the parallel fold lines adapted to fold over the covering

sheet whereby the ends of said net are confined between said ends of the blank and said covering sheet and all of said parts adapted to be folded on the longitudinal folded line, and a covering flap at one edge of the blank adapted to be secured to the 15 main portion of the blank when folded.

PAUL EDWARD HITZIGRATH.
